UNITED STATES PATENT OFFICE.

CHARLES E. AVERY, OF JERSEY CITY, NEW JERSEY, ASSIGNOR TO MANHATTAN ELECTRICAL SUPPLY COMPANY, OF NEW YORK, N. Y., A CORPORATION OF NEW YORK.

ELECTRIC SWITCH.

1,078,404.

Specification of Letters Patent. Patented Nov. 11, 1913.

Application filed April 15, 1913. Serial No. 761,266.

To all whom it may concern:

Be it known that I, CHARLES E. AVERY, a citizen of the United States of America, and residing at Jersey City, in the county of Hudson and State of New Jersey, have invented a certain new and useful Improvement in Electric Switches, of which the following is a specification.

My invention relates to electric switches and particularly to push button switches, the object of my invention being to provide a push button of improved construction possessing the advantages hereinafter pointed out.

In the accompanying drawing, Figure 1 is a vertical section through a push button switch in which my invention is shown embodied in one form; and Fig. 2 is a dropped broken elevation of the push button parts shown assembled in Fig. 1.

The switch here shown is of the type commonly employed for operating electric door bells, and to which the invention is particularly applicable, although it is not limited to this utility. This switch is provided as usual with a metal base plate 5, by means of which it may be mounted on the frame of a door or other suitable support. An insulating disk 6 which is secured in any desired manner to the plate 5, carries on its upper face the wire terminals 7 and 8. From the latter extend the spring bands 9 and 10 which form the switching contacts, normally separated but adapted to be brought into contact by the depression of the push button. The casing 11 which incloses the switch mechanism is provided with a collar 12 to guide the push button and is preferably secured to the base plate 5 by any suitable means, such for instance as screws 13. It will be understood of course that the base plate is electrically insulated as usual from all conducting parts.

The push button comprises a metallic cup 14 flared at its upper edge 15 and having securing claws 16 formed by punching downward the central portion of its base. The diameter of the body of the cup is such that it slides freely but snugly in the collar 12 of the casing. A hood 17 fits over the cup and its depending skirt 18 has a sliding fit outside the neck 12. The hood and cup are secured rigidly together by any suitable

means, as by "staking" the rim 15 of the cup to the hood. A button 19 of insulating material is secured to the lower end of the cup in any suitable manner, as by spreading the claws 16 beneath the shoulder 20 formed in the central perforation 21 of the button. This button rests upon the spring terminal 10 and is of such diameter that its upper face engages the casing 11 against which it is normally pressed by the terminal 10.

In normal position the button is pushed out by the terminal 10, into the position shown in Fig. 1. In this position the lower edge of the skirt 18 overlaps the upper edge of the neck 12 of the casing and serves to exclude moisture from the interior of the switch, which is frequently installed in positions such that it is exposed to the elements. To actuate the switch, the button is pushed in until the terminals 9 and 10 contact, thus completing the bell circuit. In this position the collar 12 occupies the space 22 afforded by the lost motion connection between the button and the casing, and which is, of course, sufficient to permit the contact 10 to be pressed into firm engagement with the contact 9.

The construction illustrated is but an exemplary embodiment of my invention and various modifications will readily suggest themselves. That shown however is simple and inexpensive, as it must be commercially for this type of switch, while at the same time efficient and serving, through the skirt of the hood, to keep moisture from the interior of the switch.

I claim as my invention:

1. In a push switch, a push button comprising a cup-shaped body, a hood secured over the open end thereof and provided with a skirt spaced from the body of the cup, in combination with a perforated insulating disk, and claws struck from the bottom of said cup-shaped body and engaging within the perforation of the disk, for the purpose described.

2. In a push switch, a push button comprising a cup-shaped body of sheet metal outwardly flared at its open end, a hood overlying said open end of the cup-shaped body and secured to the outwardly flared portion thereof, said hood having a downwardly projecting skirt spaced from the

body of the cup, in combination with a disk of insulating material centrally perforated and undercut, and claws struck downward from said cup-shaped body and spread outwardly beneath the edge of said undercut central perforation to engage said disk, substantially as described.

In testimony whereof I have signed my name to this specification, in the presence of two subscribing witnesses.

CHARLES E. AVERY.
